PULVERIZING GRANULAR MATERIALS

Trevor Andrew Smith and Ronald Holloway
 Thompson, Spordon, near Derby, England, as-
 signors to Imperial Chemical Industries Lim-
 ited, a corporation of Great Britain

Application November 28, 1939, Serial No. 306,570
 In Great Britain November 18, 1938

1 Claim. (Cl. 83—11)

This invention relates to the pulverizing of solid materials which are already granular or coarsely crushed and in particular relates to the production of finely and uniformly ground pigments.

According to the invention, the material to be pulverized is caused to pass into an apparatus such as is hereinafter more particularly described, and an air stream is at the same time caused to flow into the apparatus, the material being then subjected to pulverizing conditions in a confined space so arranged that the particles are acted upon by opposing forces, viz., a force applied by mechanical means of which the effect if it alone were acting would be that the particles would tend to stay in the confined space; an aerodynamic force of which the effect if it alone were acting would be that the particles would tend to be blown out of the confined space; the forces being so adjusted that material consisting of particles of different sizes is so worked on that the smaller particles are ejected from the apparatus in the issuing air stream whilst the larger particles remain in the confined space until they are broken down and likewise are ejected.

A pulverizing apparatus for use according to the invention comprises (i) a cylindrical, oblate spheroidal lenticular or similarly shaped casing provided with a circular or other suitable orifice, with its centre on or near the axis of the cylinder or spheroid, at one side; (ii) to rotate within said casing a vane wheel comprising a hub with vanes or a disc of less diameter than the inside of the casing, fitted with vanes on the side of the disc that faces the orifice, these vanes being fixed radially and with their planes at right angles or thereabouts to the plane of the disc, and being of such area that they almost fill the outer circular space of the casing, but their inner edges do not overlap the orifice, and the disc being also fitted with larger vanes on the other side if the stream of air through the pulverizing apparatus is to be generated wholly or partly by the rotation of said vane wheel; (iii) for introduction of the material to be pulverized into the casing one or more mouths, conveniently placed on the periphery or on the opposite side of said casing to said orifice, the mouth or mouths being so disposed that the material to be pulverized may be carried into the casing in the air stream, or may be caused to mingle with the entering air stream on arrival in the casing, and the mouth through which the air stream enters being provided with valves, dampers, blowers or the like to control, augment

or separately generate said air stream as may be desired.

The pulverization being accompanied by some generation of heat, the casing is conveniently fitted with an externally circumferentially arranged chamber for passing round it cooling liquid, e. g., cold water.

The orifice is advantageously fitted with an inward turning flange.

To the orifice is connected a suitably arranged duct, leading into a suitable hopper conveniently covered by a cloth bag filter through which the issuing air, but not the pulverized material, can pass, but the invention is not limited to this or any other particular means of recovering the pulverized material from the issuing air.

The invention will be more particularly described with reference to the drawing, in which: Figure 1 is a sectional elevation of one form of 10 the pulverizing apparatus; Figure 2 is a sectional elevation of another form of the apparatus; Figure 3 is a section showing a modified form of orifice for the casing.

Referring first to Figure 1 *a* is the casing and 20 *b* the orifice, *c* is the vane wheel rotating on shaft *e*, *d* is a mouth, connected as shown with a pipe which provides a stream of air with which also is carried the granular material to be pulverized from the hopper *h*. In this form of the 30 machine, vane-wheel *c* may have simple vanes almost filling the outer annular space in the casing as shown, and mouth *d* is then so placed that the incoming stream of air and material to be ground will be caught by the vanes as they rotate.

35 Vane-wheel *c* is driven at about 5,000 R. P. M. The flow of air being suitably adjusted finely ground material issues in the air stream from orifice *b* and is caught in a suitably placed bag filter with or without a hopper as described. A coarser material whirled around by the vanes remains within the casing until it is disintegrated by impact of particle on particle, and thus the process is continuous.

40 Figure 2 shows a form of the apparatus wherein suitable vanes are provided so that the machine acts as its own blower.

45 Here *a* is the casing, with orifice *b* adjustable in size by use of perforated plates as shown. *c* is the vane wheel rotating on shaft *e*, and consisting of a disc with large vanes *v*₂ at the side facing the mouths of the casing and small vanes *v*₁ on the side facing the orifice of the casing. By rotation of vane wheel *c* large vanes *v*₂ generate 50 a stream of air flowing around the periphery of

the vane wheel towards the orifice. Small vanes v_1 have their inner edges approximately at right angles to the disc in order that there be no generation of eddy currents in the air in the annular space between the inner edges of the vanes and the projection of the circumference of the orifice towards the disc. d_2 is the mouth which acts as air inlet provided with a valve or damper not shown. d_1 with pipe attached is the mouth for introduction of the material to be pulverized. It will be understood that these two mouths may be arranged in respect of one another in various ways, it being only necessary that the mouth which acts as air inlet shall be so set in relation to vanes v_2 that these when rotated suck air at the desired rate into the casing, and the material to be ground passes into the casing so that it becomes mingled with the entering air as that passes into the annular space between the cylindrical wall of the casing and the vane wheel.

Figure 3 shows a modified form of orifice which may be fitted if desired to the apparatus of Figure 2.

Thus, in a particular form of the apparatus according to Figure 2, the casing was a cylinder of $18\frac{1}{2}$ " internal diameter and 8" in depth from mouth to orifice, the air inlet mouth was approximately 2 sq. in. The orifice was 12" in diameter. The vane wheel, provided with vanes as shown in Figure 2, was driven at 3,200 R. P. M. Then a turkey red iron oxide was passed through at such a rate that there was no choking. In this way the issuing pulverized material was collected

at the rate of 56 lbs. per hour showing only 0.34% retained on a No. 240 B. S. S. sieve. This pigment was of much better quality than that obtained by grinding the same raw material in a mill of the kind usually used for such purposes, being brighter in the dry state and brighter in shade when used as a paint in linseed oil, and having greater colour value.

We claim:

- 10 A pulverizing apparatus comprising in combination a cylindrical-shaped casing provided with an adjustable circular discharge orifice arranged substantially coaxial with a rotor element mounted for rotation within said casing, said rotor comprising a disc member on one side of which a plurality of relatively large, radial vane members are disposed at substantially right angles to the plane of said disc, said vanes being adapted to generate a stream of air within said 15 casing upon rotation of said rotor, additional but smaller radial vane members disposed on an opposite side of said disc at approximately right angles to its face, said smaller vane members being adapted to prevent the generation of eddy 20 currents in the air in the annular spaces between their inner edges and the projection of the circumference of the orifice towards the face of said rotor, and an inlet for introducing material into 25 said casing to be subjected to the pulverizing 30 action of said rotor.

TREVOR A. SMITH.
RONALD HOLLOWAY THOMPSON.
